UNITED STATES PATENT OFFICE.

SAMEL BETTIGOLE, OF NEW HAVEN, CONNECTICUT.

CURTAIN-BRACKET.

960,792.

Specification of Letters Patent. Patented June 7, 1910.

Application filed January 15, 1910. Serial No. 538,242.

To all whom it may concern:

Be it known that I, SAMEL BETTIGOLE, a citizen of the United States, residing at New Haven, in the county of New Haven and 5 State of Connecticut, have invented a new and useful Improvement in Curtain-Brackets; and I do hereby declare the following, when taken in connection with the accompanying drawings and the numerals 10 of reference marked thereon, to be a full, clear, and exact description of the same, and which said drawings constitute part of this specification, and represent, in—

Figure 1 a broken perspective view illustrating a window frame with a bracket embodying my invention applied to each side thereof, the curtain pole and window shades being indicated in broken lines. Fig. 2 a broken sectional view illustrating the manner 20 of forming the loop for the shade brackets and method of securing the shade-brackets therein. Fig. 3 a perspective view of one of the shade-brackets detached.

This invention relates to an improvement 25 in curtain brackets, and particularly to brackets which support a curtain pole as well as window shades.

The object of the invention is a simple arrangement of parts in which a pair of 30 brackets may be employed for supporting a curtain pole and two shade rollers so that one shade roller may be mounted inside the window frame and the other outside; and the invention consists in the construction 35 hereinafter described and particularly recited in the claim.

In carrying out my invention, I form a curtain pole arm 2 and a back 3 from a single strip of flat sheet metal, the arm projecting 40 at right angles from the upper end of the back and bowed at the outer end in the usual manner to receive a curtain pole. The strip forming the back is folded above its lower end to form a loop 4 and in this 45 loop a set screw 5 is mounted. Extending through the loop are two slides 6 and 7. One of the slides 7 has an outwardly projecting arm 8 and the other slide 6 has an inwardly projecting arm 9. These brackets 50 are arranged in pairs, and one of the arms 8 has the usual round perforation 10 for one

end of the shade-holder, while the other has a longitudinal slot 11 for the other or spring end of the shade roller. These brackets are made right and left and are secured to the 55 outer face of the window casing, and the arms 9 extend in toward the window sash so that one shade is supported within the casing, while the arms of the other bracket project outward beyond the window-casing 60 so that the second shade overlaps the sides of the window-casing, a common arrangement in hanging two shades at a window. These brackets are longitudinally adjustable in the loops 4 so that they may be readily adapted 65 for use with shade rollers of different lengths, the arms being clamped in place by the set screws 5. As the arms are longitudinally adjustable, they may be moved to have the spring ends of the rollers engage with 70 the slots 11 instead of having open slots into which the spring ends may be inserted as is customary in window-shade brackets. The bracket arms, like the pole-arm and back, are formed from sheet metal and are readily 75 struck up, and can therefore be produced at a very low cost. The device is extremely simple and may be attached to a window frame by screws, two screws for each bracket being sufficient to support the device so that 80 but only four screws are required to support the curtain pole, and two window shade holders.

I claim:—

A curtain bracket formed from a single 85 strip of metal and comprising a curtain pole arm and a back, the back formed above its lower end with a loop, two slides adjustably mounted in said loop, a clamping screw extending through said loop and adapted to 90 clamp the said slide against the back, one of said slides formed with an outwardly projecting shade-supporting arm, and the other slide with an inwardly projecting shade supporting arm. 95

In testimony whereof, I have signed this specification in the presence of two subscribing witnesses.

SAMEL BETTIGOLE.
